UNITED STATES PATENT OFFICE

MORRIS M. RIVELIS, OF PHILADELPHIA, PENNSYLVANIA

ART OF MAKING CUT-STEEL ORNAMENTS

Application filed August 17, 1928. Serial No. 300,247.

My invention relates to a new and useful improvement in the art of making cut steel ornaments, and it relates more particularly to a novel construction in cut steel ornaments whereby a more completely finished ornament may be produced with a considerable saving of labor and at a corresponding lesser cost, and whereby, moreover, a more desirable product is produced.

10 It has been the practice in mounting cut steel ornaments with "open work", that is, designs having parts cut out, to place a piece of black or other colored leather, velvet or other suitable material back of the ornament 15 so as to give a suitable background at the "cut out" parts of the design.

The production of these cut-out or "open" design cut-steel ornaments has heretofore entailed considerable labor and corresponding 20 cost in the formation of the sheet metal blanks because the interior parts of the design are cut out with a great deal of difficulty and require extreme skill and care.

According to my novel method and construction, I am enabled to produce a cut-steel ornament which will have the background or "backing" built into the ornament and which may be made in "open" designs as distinguished from merely solid designs, without 30 out the necessity of actually cutting out the interior parts of the design from the sheet metal base of the ornament.

According to my invention I form a sheet metal base having its outer edge or border 35 conforming to the outer border of the design and having all the perforations corresponding to the cut-steel "points" or nails of the particular design. I superimpose upon this sheet metal base a suitably colored "backing" 40 sheet having the same contour as the metallic base sheet also having the perforations therein, and then mount the cut-steel "points" or nails directly upon the backing sheet with the stems thereof extending through the backing sheet and through the metallic base sheet in 45 which they are firmly secured by riveting.

By this novel method and construction, the cut-steel "points" or nails are mounted directly upon the colored backing sheet or 50 "filler" instead of upon the metallic base sheet,

with the result that any "open" design may be set off against the suitably colored background without any actual "open" work in either the metallic base sheet or in the backing or filler sheet.

55 For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

60 In the accompanying drawings, in which like reference characters indicate like parts:—

65 Figure 1 represents a top plan view of a metallic base sheet or blank adapted for an "open" design cut-steel ornament embodying my invention.

70 Figure 2 represents a plan view of a completed cut-steel ornament made according to my invention.

75 Figure 3 represents a section on line 3—3 of Figure 2, on a greatly enlarged scale, illustrating the construction of the completed ornament.

80 Figure 4 represents a plan view of a "filling" or backing sheet or blank, adapted for a cut-steel ornament embodying my invention but having the multi-color backing or "filler".

85 Figure 5 represents a plan view of the interior or upper backing or "filler" sheet adapted for a cut-steel ornament with a multi-color backing or "filler".

90 Figure 6 represents a top plan view of a cut-steel ornament embodying my invention having a multi-color backing or "filler".

95 Figure 7 represents a section on line 7—7 of Figure 6, on a greatly enlarged scale, illustrating the construction of a cut-steel ornament having a multi-color backing or "filler".

100 In carrying out my invention, I prepare the metallic base sheet 8 according to any suitable design by perforating the sheet according to the particular design, as at 9, and

by suitably scalloping the outer border of the sheet, as at 10. All the interior border design of the particular pattern is omitted, thus leaving the sheet "solid" except for the perforations of the design or pattern. A backing or "filler" sheet 11 of some non-metallic material as, for instance, celluloid, viscaloid, or the like, of any desired color as, for instance, black, is then perforated and cut along its outermost border identical with the metallic base sheet 8 and is superimposed thereon. The various cut-steel "points" or nails 12 are then mounted upon the "filler" sheet 11 as indicated in Figures 2 and 3, by extending the stems 13 thereof first through the backing or "filler" sheet 11 and then through the metallic base sheet 8, cutting the stems at the rear surface of the metallic base sheet 8 and riveting the same as at 14, thereby not only firmly mounting the cut-steel "points" or nails 12, but at the same time permanently and firmly uniting the base sheet 8 and "filler" sheet 11. The "open" spaces of the design, indicated by the numeral 15, are thus filled in by the "filler" sheet 11 which, as pointed out heretofore, may be of any suitable color to match the particular wearing apparel with which the cut-steel ornament is to be worn as, for instance, the shoes, hat or dress, or the like. The supporting bar 16 by means of which the ornament is finally supported on the shoe, dress, or the like, is affixed to the rear of the metallic base sheet in the usual manner by one of the border row of cut-steel "points" or 35 nails 12.

By my novel method and construction, it is also possible to produce a backing or "filling" in an "open" design of more than one color, as indicated in Figures 4 to 7 inclusive. Thus if it is desired to fill or "back" certain parts of the design by one color filling or backing and to fill or "back" other parts of the design or pattern by a different color, I provide two or more differently colored "filler" or backing sheets as, for instance, the sheets 17 and 18. Thus I first provide a "filler" sheet 17 of one color as, for instance, black, covering the entire design or pattern that is identical with the metallic base sheet, (which latter is not shown separately in the figures). I then prepare a second "filler" sheet 18 of a different color as, for instance, yellow, having the shape and perforations of only a part of the entire pattern as, for instance, the shape and perforations of the butterfly part 19 of the particular pattern shown in Figure 6.

The large filler sheet 17 is first superimposed upon the metallic base sheet 8, as indicated in Figure 7, and the smaller or interior filler sheet 18, of a different color, is then superimposed upon the filler sheet 17 in registering alignment with the particular part of the pattern which is to be filled with a different color as, for instance, the butterfly

part 19 of the pattern or design shown in Figure 6. The cut-steel nails or "points" 20 of the outer design are then mounted upon the outer filling sheet 17, as shown in Figure 7, while the cut-steel "points" or nails 21 of the inner part of the design are mounted upon the inner filler sheet 18 and extend through both the inner and outer filler sheets 18 and 17, respectively, and similarly riveted on the rear surface of the metallic base sheet 8 as indicated in Figure 7.

The advantages of my novel improvement in the art of making cut-steel ornaments are manifold. The cost of producing intricate "open" designs or patterns is greatly reduced because of the total elimination of all "cut-outs" in the metallic base sheet. By building the backing or "filling" as a permanent part of the cut-steel ornament, the use of a separate leather, velvet or similar "backing" is entirely eliminated and the cost of mounting said backing is also eliminated.

By the use of my novel method and construction in the art of making cut-steel ornaments, not only may "open" designs or patterns be produced at a lower cost, but more intricate and greater variety of designs may be produced with better effects since entirely detached configurations may be provided with in a design which has heretofore been entirely impossible in making cut-steel ornaments by virtue of the inherent construction of cut-steel ornaments as produced heretofore.

Thus I may provide such disconnected or unattached pattern features or design parts as indicated at 22, in Figure 6, which are not connected to the other parts of the design by any features of the pattern. This type of design is entirely impossible in cut-steel ornaments as made heretofore because it would be necessary to cut out the base sheet around the entire design element 22, thereby leaving the same without any physical support.

Thus by my novel method and construction practically any intricate design may be produced with the same facility and without any greater cost than simple designs excepting for the cost of material such as additional cut-steel "points" or nails.

The backing or "filling" sheets 11, 17 and 18 may be any suitable, but preferably hard, non-metallic material as, for instance, celluloid, vulcanized fibre, artificial or natural resinous material, or the like, since the completed ornament does not depend upon the "filler" or backing sheet for its support or rigidity, but merely for the "filling" or backing effect. Thus, too, the "filling" or backing sheets 11, 17 and 18 may be comparatively thin so as to add very little to the total thickness of the ornament.

I am aware that the invention may be embodied in other specific forms without departing from the spirit or essential attributes thereof, and I therefore desire the present

embodiment to be considered in all respects as illustrative and not restrictive, reference being had to the appended claims rather than to the foregoing description to indicate the scope of the invention.

5 Having thus described my invention what I claim as new and desire to secure by Letters Patent, is:—

10 1. A cut-steel ornament comprising a metallic base sheet, a filler sheet of suitable color superimposed thereon, and cut-steel points mounted upon said filler sheet in any predetermined design having their stems extending through said filler sheet and base sheet permanently anchored in the latter.

15 2. A cut-steel ornament comprising a metallic base sheet, a non-metallic filler sheet of suitable color superimposed thereon, and cut-steel points mounted upon said filler sheet in any predetermined design having their stems extending through said filler sheet and base sheet permanently anchored in the latter.

20 3. A metallic base sheet having perforations extending therethrough arranged according to a predetermined pattern and having the border thereof composed of a series of generally circular edge portions formed about the series of border row perforations, a suitably colored filler sheet superimposed upon said base sheet having perforations extending therethrough and a border corresponding to and generally registering with the perforations and border of the base sheet, and cut-steel points mounted upon said filler sheet in said perforations having their stems extending through said filler sheet and base sheet and permanently anchored in the latter.

25 4. A metallic base sheet having perforations extending therethrough arranged according to a predetermined pattern and having the border thereof composed of a series of generally circular edge portions formed about the series of border row perforations, a suitably colored non-metallic filler sheet superimposed upon said base sheet having perforations extending therethrough and a border corresponding to and generally registering with the perforations and border of the base sheet, and cut-steel points mounted upon said filler sheet in said perforations having their stems extending through said filler sheet and base sheet and permanently anchored in the latter.

30 5. A cut-steel ornament comprising a base sheet, a plurality of differently colored filler sheets superimposed upon said base sheet, and cut-steel points mounted upon said plurality of colored filler sheets with their stems extending through said filler sheets and through said base sheet and permanently anchored in the latter.

35 6. A cut-steel ornament comprising a base sheet, a plurality of differently colored non-metallic filler sheets superimposed upon said base sheet, and cut-steel points mounted upon

said plurality of colored filler sheets with their stems extending through said filler sheets and through said base sheet and permanently anchored in the latter.

7. A cut-steel ornament comprising a metallic base sheet, a plurality of differently colored non-metallic filler sheets superimposed upon said base sheet, and cut-steel points mounted upon said plurality of colored filler sheets with their stems extending through said filler sheets and through said base sheet and permanently anchored in the latter.

75 8. A cut-steel ornament comprising a metallic base sheet having a series of perforations arranged according to a predetermined pattern and having the border thereof composed of a series of generally circular edge portions arranged about the series of border row perforations, a suitably colored filler sheet superimposed upon said base sheet and generally co-extensive therewith and having a corresponding and registering series of perforations and border, a differently colored filler sheet superimposed upon said first filler sheet and of an area less than said first filler sheet having perforations corresponding to and registering with the perforations in said first filler sheet covered thereby and having a border also formed of a series of generally circular edge portions formed about the series of border row perforations, and cut steel points mounted upon said filler sheets with their stems extending therethrough and through said base sheet and permanently anchored in the latter.

80 9. A cut-steel ornament comprising a metallic base sheet having a series of perforations arranged according to a predetermined pattern and having the border thereof composed of a series of generally circular edge portions arranged about the series of border row perforations, a suitably colored non-metallic filler sheet superimposed upon said base sheet and generally co-extensive therewith and having a corresponding and registering series of perforations and border, a differently colored non-metallic filler sheet superimposed upon said first filler sheet and of an area less than said first filler sheet,

85 having perforations corresponding to and registering with the perforations in said first filler sheet covered thereby and having a border also formed of a series of generally circular edge portions formed about the series of border row perforations, and cut steel points mounted upon said filler sheets with their stems extending therethrough and through said base sheet and permanently anchored in the latter.

90 10. An ornament comprising a base sheet, a filler sheet superimposed thereon, and cut steel points mounted upon said filler sheet in any predetermined design, having stems

extending through said filler sheet and permanently anchored in said base sheet.

11. A cut-steel ornament comprising a base sheet, a coloring layer superimposed thereon, and cut-steel points mounted in predetermined design, in contrasting relation to the coloring layer.

12. A cut-steel ornament comprising a base sheet, a coloring layer superimposed thereon, and cut-steel points mounted in predetermined design, in contrasting relation to the coloring layer and anchored to said base sheet.

13. A cut-steel ornament comprising a base sheet, a coloring layer superimposed thereon, and cut-steel points mounted in predetermined design, in contrasting relation to the coloring layer and having stems anchored in said base sheet.

20. In testimony whereof I have hereunto set my hand this 7th day of August, 1928.
